Ronald A. Marr, Barberton, Ohio

Application July 21, 1945, Serial No. 120,858

Term of patent 14 years

(Cl. D34—5)

To all whom it may concern:

Be it known that I, Ronald A. Marr, a citizen of the United States and a resident of Barberton, in the county of Summit and State of Ohio, have invented a new, original, and ornamental Design for a Golf Putting Game Device, of which the following is a specification, reference being had to the accompanying drawing, forming part thereof.

In the drawing:

I claim:

The ornamental design for a golf putting game device, as shown.

RONALD A. MARR.
